Primary Examiner — Messina L Smith*Assistant Examiner* — Aram Kwon(74) *Attorney, Agent, or Firm* — McAndrews Held & Malloy, Ltd.(57) **CLAIM**

The ornamental design for a speaker, as shown and described.

DESCRIPTION

FIG. 1 is a front perspective view of a speaker showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The dashed broken lines in the figures illustrate portions of the speaker that form no part of the claimed design.
